GRAVITY THERMAL DILATOR

William P. B. Nemzek, North Arlington, N. J.

Application March 16, 1935, Serial No. 11,377

2 Claims. (Cl. 128—255)

The invention relates to a gravity thermal dilator to be utilized for the application of heat to the walls of the body cavities in the pelvic region, and more particularly the vagina.

One of the important objects of the invention is the provision of an applicator of such simple construction that it may readily be inserted by the patient in the privacy of the home.

Known devices of this character having similar functions are complicated and involved and are only capable of being used in a hospital or a doctor's office as it is imperative that either a doctor or a competent nurse be in attendance, not only to insert the applicator, but to be on hand while the treatment is being given.

Other objects and advantages will become apparent as this specification proceeds. Referring to the drawings forming a part thereof and in which one form of the invention is illustrated:

Fig. 1 is a general assembly view of the apparatus with parts broken out and parts broken away;

Fig. 2 is a longitudinal sectional view of the applicator;

Fig. 3 is a cross sectional view taken on line 3—3 of Fig. 2, the expandable member being shown in broken lines in the dilated position;

Fig. 4 is a sectional view of a valve used to control the flow of the heating fluid; and

Fig. 5 is a top plan view of said valve.

Referring again to said drawings the reference numeral 10 designates an insulated container. This container may be of the double wall type having a vacuum space 11 between the walls 12 and 13. It is provided with a hook 14 for suspending it at any desired height and a closure member 16 having a suitable vent 17. The container 10 may be suspended at the desired height on a wall, or a stand, adjustable as to height may be provided. The fact of the container being portable and that its elevation may be easily and quickly varied is of importance because the elevation of the container materially aids in controlling the dilation of the expandable member, hereinafter described. For purposes of illustration an upright or stand 18 having a plurality of hooks or pins 19 is shown.

The lower part of the container has an outlet 20 to which a flexible hose 21 may be attached. The other end of the flexible hose 21 is secured to the inlet 22 of the applicator 23. The hose 21 is provided with a conventional shut off clamp 24.

The applicator 23 comprises a body member 25. This body member is annular in cross section and

is formed of semi-hard rubber. It has two longitudinal passages 26 and 27 and a rounded end portion 28. The passage 26 may be termed the inlet passage and a metal nipple 22 may be inserted therein to facilitate attaching the hose 19. The passage 27 may be termed the outlet passage and is provided with a nipple 29 to which another length of flexible hose 30 may be attached.

Removably secured to the body member 25 is an expandable bag 31. This bag has a neck portion 32 which snugly fits about the body portion 25. The expandable member 31 has bi-lateral extensions 33 and a pocket 34 at its upper control region. The pocket 34 is made to conform with the rounded end 28 of the body member. Removably secured to the body member 25 is an expandable bag 31. This bag has a neck portion 32 which snugly fits about the body portion 25. The expandable member 31 has bi-lateral extensions 33 and a pocket 34 at its upper control region. The pocket 34 is made to conform with the rounded end 28 of the body member. The expandable member is made of a comparatively thin elastic material and when the neck portion 32 is slipped over the body portion 25 the pocket 34 functions to center and position the expandable member in relation to the body portion. The core or body-portion thus passes through the expandable member and this is quite important as it greatly helps in the insertion of the applicator. In the act of inserting the core acts as a support for the expandable member and in view of the expandable member not being secured to the end of the core a free and easy and equally distributed dilation is obtainable. This, in connection with the removability of the expandable member is considered an important feature of the invention. The expandable member 31 obviously is the part of the applicator that will wear out the quickest. This member is comparatively inexpensive and in accordance with the invention may be easily and quickly renewed.

The body portion 25 may be provided with an annular groove 35 to facilitate holding the expandable member in position and in addition the neck portion 32 may have a reinforced bead 36 to further aid in maintaining the position of the expandable member.

The flexible hose 30 forms the outlet from the applicator and is provided with a valve 40 for controlling the rate of flow. With the valve 40 shown in the position of Figs. 4 and 5 the flow is cut off entirely. When the valve handle 41 is turned clockwise and abuts the stop 42 the valve is cracked or opened slightly and the liquid flows slowly. When the handle 41 is turned counter-clockwise and abuts the stop 43 the valve is fully open. Obviously it may be set for any intermediate position. Numerous other methods may be utilized to control the size of the outlet 30.

In operation the container 10 is filled with 55

water heated to the predetermined temperature and the container being insulated this temperature is substantially maintained for the required length of time. The handle of the shut off clamp 5 22 is depressed so that no water may flow through the hose 19. The valve 41 is then set according to the doctor's instructions as to the length of time the treatment is to last and as to the amount of dilation desired. The applicator 23 is 10 inserted into the vagina or other body cavity. It is desired to point out at this time that the applicator is as easily inserted into the vagina as any ordinary douche nozzle with which every woman is familiar. The handle of the shut off clamp 22 is raised and the water entering the applicator dilates the bilateral extensions. The dilated position is illustrated in broken lines in 15 Fig. 3.

Another one of the important aspects of the 20 invention is that the amount of dilation of the applicator is controlled by the elevation of the container and the size of the outlet opening which is controlled by the valve 40.

Changes in details of construction such as 25 would occur to one skilled in the art are to be considered as coming within the spirit of the invention and the scope of the appended claims.

I claim:

1. An applicator for a thermal dilator, said applicator having in combination, a body-portion formed of semi-hard rubber, a rounded end on 30

said body-portion, a removable expandible member, a neck-portion on said removable expandible member, said neck-portion snugly engaging the body-portion of said applicator, bilateral extensions on said expandible member, a pocket formed 5 between said bilateral extensions, said pocket being adapted to cooperate with the rounded end of said body-portion, an inlet for said applicator, and an outlet for said applicator, said inlet and said outlet comprising ducts formed in the rubber 10 body-portion of said applicator.

2. An applicator for a thermal dilator, said applicator having in combination, a body-portion formed of semi-hard rubber, a removable expandible member having bi-lateral extensions and a neck portion, said body-portion entering into and extending to the upper region of said removable expandible member whereby said removable expandible member freely embraces the upper part of 15 said body portion, said bi-lateral extensions being free to move away from said body portion under dilation, the neck portion of said removable expandible member snugly engaging said body portion, an inlet for said applicator, and an outlet 20 comprising ducts formed in the rubber body-portion of said applicator whereby fluid may enter and pass out so as to maintain dilation in the bi-lateral extensions of said removable expandible member.

WILLIAM P. B. NEMZEK.
